UNITED STATES PATENT OFFICE.

JOHN J. MILLER, OF CHICAGO, ILLINOIS.

ELECTRIC SIGNALING SYSTEM FOR RAILROADS.

Application filed August 9, 1922. Serial No. 580,878.

To all whom it may concern:

Be it known that I, JOHN J. MILLER, a citizen of the United States, residing at Chicago, in the county of Cook and State of Illinois, have invented certain new and useful Improvements in an Electric Signaling System for Railroads; and I do hereby declare the following to be a full, clear, and exact description of the invention, such as will enable others skilled in the art to which it appertains to make and use the same.

This invention relates to improvements in railway signaling systems, and has for its principal object the provision of an electrically operated equipment for signaling to be used on steam railroads and all intersecting highways, public and private, or the like, wherein the electricity is produced on the train by a belt or other means from the revolving wheels to a dynamo, the latter furnishing electricity directly to the signaling system, or indirectly through a storage battery.

One of the principal objects of this invention is the provision of a signaling system for railroads which will be automatically operated on other lines besides the line upon which the train is running, and which need not be restricted to the ordinary signaling means and objects now in use. The plan provides for operating signals, switches, gates, etc., at any road crossing or at any point on the right-of-way, as well as for signaling to intersecting lines, all of which is accomplished by the device of the invention.

Another important object of this invention is the provision of an electric signaling system for railroads which will indicate positively whether the train in a block is moving or standing still, and will operate signals in either case. This may be accomplished by separate connections with a dynamo, and with a storage battery on the moving train so provided that the connections with the dynamo indicate that the train is in motion, and those with the battery indicate that the train is standing still.

Still another object of this invention is the provision of an electric signaling system for railroads or the like, whereby signals are operated both in advance and in the rear of the moving train on its own line, as well as on intersecting lines as desired.

One of the particular objects of this in-

vention is the provision of an insulated third rail for carrying electric current from the train dynamo or battery through an ordinary brush or other means moving with the train to a signaling equipment.

Other and further important objects of this invention will be apparent from the disclosures in the accompanying drawings and following specifications.

The invention, in a preferred form, is illustrated in the drawings, and hereinafter more fully described.

In the drawings:

Fig. 1 is a plan view of a railroad crossing showing diagrammatically one of the improved signaling arrangements of this invention.

Fig. 2 is a sectional view showing the method of application of the moving brushes carried on the car to the main rail and to the third rail.

Fig. 3 is a plan view similar to Fig. 1, showing an arrangement whereby both or either a generator or battery may be used to operate the signaling means.

Fig. 4 is a sectional view showing the third rail connection to be used in connection with the device illustrated in Fig. 3.

Fig. 5 is a plan view showing the invention as applied to a block in a single line of track with the crossing eliminated.

Fig. 6 is a view similar to Fig. 5 showing the invention wherein both generator and battery connections are used.

As shown in the drawings:

The reference numeral 10 indicates generally the truck or supporting wheels of a train or car adapted to be driven or propelled along rails 12. The car is provided with a generator 14 operated by a belt 15, or other suitable means driven from the axle of the wheel 10 in an obvious manner. In connection with the generator 14 is provided a storage battery, as illustrated at 16, connected in parallel with the generator, and with connection to the third rail 18 and to the main rail 12 of the track. As illustrated in Figs. 1 and 4 the wires 20 and 22 pass from the generator 14 through an automatic cutout 24 then to the two terminals of the battery 16, and are thence connected to proper terminals on the brushes designated as 26 and 28 respectively, and applied upon the main rail 12 and third rail 18, as illustrated in Fig. 2, or any other convenient form of current carrying means.

Fig. 1, as hereinbefore stated, illustrates a crossing of two different lines of railroads, wherein signaling means are provided to warn trains on one line coming from either direction, of the approach to the crossing, of trains on the other line from either direction. For purposes of convenience, the trains coming into the crossing are designated as Roman Nos. I, II, III and IV, going around the drawing in an anti-clockwise direction, and the respective circuits and signaling systems operated by such trains will be likewise so designated by Arabic numerals. It will be seen that the circuit consisting of conductors, to signals operated by train No. 1 upon its approach to the crossing, is designated by the numeral 1, and this circuit of the brushes 26 and 28 is completed by the contact with the third rail 18 and main rail 12, which contact may be out along the track 12 from the crossing within the block for any desired distance. If desired, the third rail or other conductor on the crossing line may be utilized to carry current to the signals.

The third rail 18 in each case is broken or insulated for a short distance extending upon the farther side of the crossing, and is then again taken up in the shape of an additional third rail 48 which operates a different set of block signals which merely indicate the presence of the train to another train on the same track behind the first train, and has no connection with the crossing signals hereinbefore described. The system operated by the third rail 48 is herein illustrated for purpose of convenience in Fig. 1 and is more fully described in connection with the drawings of Fig. 5.

Returning to Fig. 1 it will be seen that when the truck of train No. 1 enters within a predetermined distance from the crossing, and the brush 26 contacts with the third rail 18, a circuit will be immediately closed, as illustrated, by following the wires numbered 1 and the signals numbered 1^a, 1^b, 1^c, around the crossing, as illustrated. The first signal designated by the character 1^a will be operated by train No. 1, and is located alongside the right-hand track 12, upon which train No. 1 is running, and will indicate to the engineer of that train that the block system and the signals in circuit therewith are in operating condition, as all of the signals along this line are connected in series.

From the signal 1^a, the current is carried along the wire 1, as illustrated, to the signal 1^b, which in the drawings is shown as located adjacent the crossing, and at the right-hand side of the track upon which train No. 2 might be approaching said crossing. It is obvious, of course, that the signal 1^b may be one or more of a plurality of signals all in the same circuit, and distributed at dif-

ferent positions back along the line of approach of train No. 2 as far as is desired or convenient, so that ample notice of the presence of train No. 1 in the block may be communicated in advance to the operator of train No. 2.

From signal 1^b wire 1 is carried across the tracks of train No. 3, and here the signal may be omitted, if desired. From thence the wire or other conductor travels to signal 1^c, positioned at the right-hand side of the track upon which train No. 4 might be approaching the crossing, and which, as described in connection with train No. 2, might consist of a plurality of signals distributed at convenient points back along the line of approach of train No. 4 for any desired distance from the crossing, and connected either in series or parallel. From thence the current is carried, as shown by the wire No. 1, back to the main rail 12 of the track of approach of train No. 1, and into the brush 28 by said train. Any other arrangement of circuits which will be equivalent or produce the same effect, is part of the invention.

A similar condition exists with regard to the circuits operated by trains Nos. 2, 3 and 4 respectively, as indicated by the wires and block systems designated as 2^a, 2^b and 2^c; 3^a, 3^b and 3^c, and 4^a, 4^b and 4^c.

A modification of the invention is illustrated in Figs. 3 and 4, wherein a combination of signaling means operated by either the battery or the generator present on the train, or by both, if it is desired, may be used. This combination will be particularly useful in indicating to the engineers of other and approaching trains whether the train which has set the block signal against the second train is either in motion or standing still, as when signals operated solely by the generator are in view, it will be evident that the train is in motion, and vice versa.

As shown in the drawings, the generator 14, driven by the trucks 10, by means of the belt 15, is provided, together with the battery 16, and wires 20 and 22 connecting the battery in parallel with the generator, and with the track 12 and the third rail 18. In this figure there is shown beside the wires 20 and 22, additional current carrying wires 30 and 32, which lead from the generator 14 to the main rail 12, and to an additional current carrying means in the form of another third rail 34 respectively. As illustrated, the wires 30 and 32 are taken off from the generator 14 at a point upon the side of the cutout 24 removed from the battery 16, so that no short circuiting of the battery will result. An additional brush 36, as shown in Fig. 4, is provided on the second third rail 34.

As shown in Fig. 3, in addition to the regular system of signals 1^a, 1^b and 1^c, 2^a, 2^b and 2^c, etc., as represented in Fig. 1, an

additional series is provided designated as 1^a, 1^e, and 1^f, etc., operated directly by the dynamo 14, and intended to indicate that the train approaching the crossing is in motion at the time such indicator or signal is being operated. The circuits illustrating the current carrying means which conveys the generator current are illustrated by wires 1^g, 2^g, 3^g and 4^g respectively. As illustrated, 10 the connection from the last signals 1^e and 1^f to the main conducting means 12 is carried by only one wire designated as No. 1, and it will be obvious that here one wire will be sufficient to return the current to the main rail 12, no matter whether its origin be in the battery 16 or the generator 14.

If desired or convenient a single wire may be arranged to convey the current from both the battery and generator onto the system of signals with a resistance element, cutout or relay, installed between the signals operated by the dynamo and generator respectively, so that the first set of signals as designated by the characters A, B and C will be operated in all events, by either the battery or the generator, and when the current is sufficient, as when the dynamo is in operation, the second set of signals, designated by D, E and F, will be additionally operated on account of the different voltage or amperage, or both from the generator 14, which will operate through the resistance or through the relay, as convenient.

As illustrated in Fig. 5, a system comprising a battery 16, generator 14, third rail 48 and main rail 12, similar to that shown in Fig. 1, is used in connection with a straight line track and a single block, whereby the presence of the train may be indicated in advance for moving purposes at crossings, etc., and is indicated in the rear of the passage of said train, forming a block for the train while in motion, or standing still, to indicate its presence to the train following. 40 The third rail is designated as 48 in order to correspond with the third rail illustrated at that point in Fig. 1, and is provided with the wire 50 leading therefrom to a signal 52 in advance of the train, from whence is connected a wire 54 leading back to the main rail 12. In the rear of the train and adapted to be continuously operated after the passage of same, but while still in the block, is constructed a rear signaling means illustrated at 56, having a pair of wires 58 and 60 leading therefrom to the third rail 48 and the main rail 12 respectively. A plurality of such signals may be used, if desired, or necessary.

As will be evident, the signals 52 and 56 will be operated as long as the train is in the block, thereby indicating the approach of the train to observers in advance, and also indicating that the same has passed by means of the signal 56, whereby other trains

will be prevented from running into the rear thereof.

The modification illustrated in Fig. 6 describes a block system similar to that shown in Fig. 5, but which is operated by both the battery 16 and the dynamo 14, by means of two third rails or other conductors 18 and 34 respectively. As shown, the signals 52 and 56 are operated by means of the battery current, as in Fig. 5, and the signals 62 and 66 are operated by means of the generator current carried through separate wires 68 and 70 from the secondary third rail 34. If desired a resistance element or cutout may be installed between the signals 52 and 62 and 56 and 66 respectively, so that only one set of wires or one rail or other conducting means will be necessary, and with either the battery or generator, or both, as has been hereinabove described.

It will be obvious that instead of the operation of lamps for signals, the ordinary arm block system may be installed and operated by means of this invention, or, in the event that the current is found not to be sufficient, a relay operating local batteries may be readily installed in connection therewith, so as to insure the positive operation of the system at any point. Further, the system may be extended to include signals of various kinds to other vehicles besides oncoming trains, such as approaching automobiles on crossings, or to pedestrians or the like, and also for the operation of gates, switches, horns, bells, etc. Further, in the event that two converging lines cross each other at an angle of less than a right angle, the signaling wires may, if desired, be carried directly across country to the signals by which the other train is desired to be warned. It is preferable that the apparatus be placed upon the engine, coal tender, or baggage car, which will always be a part of the train, and it is evident that only one car on the train will be needed to carry the equipment. Many hundreds of batteries now commonly used by the average railroad system can be replaced or displaced, with great saving, and many crossings and all road intersections heretofore unprotected, can, by this method, be protected on one or more lines with a minimum of expense.

In the event that the motion of any train or any car is reversed, an automatic reversible switch, installed in connection with the cutout, is put into operation, so that proper current connections with the battery are maintained at all times.

I am aware that many changes may be made and numerous details of construction varied throughout a wide range, without departing from the principles of this invention, and I therefore do not purpose limiting the patent granted hereon otherwise than as necessitated by the prior art.

I claim as my invention:

A railway grade crossing signaling system including a track, a third rail parallel with the track, a car adapted to move along the track, electrical generating means on the car and connected to said third rail and operated thereby when the car is in motion, a second third rail parallel to the first third rail, a storage battery in parallel connection with said generator and connected to said second third rail, and similar track and set of third rails crossing the first track, sets of signaling means located on each of said tracks,

current conducting means connected to all of one set of said signaling means on one side of said tracks, the current conducting means being connected to one of the third rails and to one of the main rails of the track respectively, a second set of signaling means on said track adapted to be actuated by current directly from the generator and acting in conjunction with the first named signaling means and at practically same position along said tracks. 15

In testimony whereof I affix my signature.

JOHN J. MILLER. 20
